United States Patent Office

Des. 185,104
Patented May 5, 1959

185,104

FAN

Ottis D. Twist, Mount Sterling, Ill.

Application April 10, 1958, Serial No. 50,426

Term of patent 14 years

(Cl. D26—7)

Fig. 1 is a front view of a fan embodying my new design; Fig. 2 is a back view thereof; Fig. 3 is an edge view thereof in the direction of arrows 3—3 of Fig. 2; and Fig. 4 is an enlarged transverse sectional view thereof on line 4—4 of Fig. 2.

I claim:

The ornamental design for a fan, substantially as shown.
